UNITED STATES PATENT OFFICE.

JOHN H. WIGGINS, OF BARTLESVILLE, OKLAHOMA.

FLOATING DECK FOR LIQUID-STORAGE TANKS.

Application filed December 14, 1923. Serial No. 680,773.

To all whom it may concern:

Be it known that I, JOHN H. WIGGINS, a citizen of the United States, residing at Bartlesville, Oklahoma, have invented a certain new and useful Improvement in Floating Decks for Liquid-Storage Tanks, of which the following is a full, clear, and exact description, such as will enable others skilled in the art to which it appertains to make and use the same.

This invention relates to floating decks for liquid storage tanks of the type that comprise a portion which floats upon and is supported by the liquid in the tank.

In floating decks of the general type referred to there is a tendency for the outer edge of the portion of the deck supported by the liquid to sag or deflect downwardly when it is subjected to an excessive load and the main object of my invention is to increase the buoyancy of such floating decks.

To this end I have devised a floating deck that comprises a portion constructed either in the form of a limber or rigid sheet that floats upon the liquid in the tank, and pontoons or buoyant devices positioned adjacent the outer edge of said portion and arranged in engagement with the liquid in the tank for increasing the buoyancy of said portion at its outer edge sufficiently to compensate for a heavy load that tends to deflect the outer edge of said portion. I have herein illustrated my invention embodied in a floating deck of the type that comprises a central body portion that floats on the liquid in the tank, and a variable peripheral portion for closing the annular space between said central portion and the side wall of the tank, but I wish it to be understood that my invention is applicable to any type or kind of floating deck.

Figure 1 of the drawings is a vertical transverse sectional view of a liquid storage tank equipped with a floating deck constructed in accordance with my invention.

Figure 2 is a horizontal sectional view, taken on the line 2—2 of Figure 1.

Figure 3 is a detail vertical sectional view of one of the pontoons; and

Figure 4 is an enlarged vertical sectional view, illustrating the construction of the va-

riable peripheral portion of the deck shown in Figure 1.

Referring to the drawings which illustrate one form of my invention, A designates the side wall of a liquid storage tank, B designates the central body portion of a floating deck that covers the major portion of the surface of the liquid in the tank, C designates a number of segmental shoe members that bear against the inner side of the side wall of the tank and which co-operate with each other to form an annular shoe whose lower edge portion is submerged in the liquid in the tank and D designates the horizontally-disposed elements that project inwardly from said shoe members towards a vertically-disposed annular rim E on the central body portion of the deck, said shoe members co-operating with the horizontally-disposed elements D to form a variable peripheral portion that closes the annular space between the side wall of the tank and the vertical rim E on the central body portion of the deck. The variable peripheral portion of the deck, formed by the shoe members C and elements D, is carried by pivotally mounted hangers or supports F mounted on the central body portion B of the deck in such a way as to permit the co-operating sections of the variable peripheral portion of the deck to move radially with respect to the central body portion of the deck. As shown in Figure 1, two hangers F are provided for each section of the peripheral portion of the deck, each of which hangers consists of a substantially elbow-shaped lever arranged with its vertical leg projecting upwardly from the rim E on the central body portion of the deck and its horizontal leg projecting outwardly towards the side wall A of the tank. The lower end of the vertical leg of each of the hangers F is pivotally connected to a bracket 1 on the rim E and the horizontal leg of each of said hangers is connected by a swinging link 2 to the particular section of the peripheral portion of the deck with which it co-operates, thereby permitting the various sections of the peripheral portion of the deck to move radially without destroying the parallel relationship between the shoe

2

members C and the side wall of the tank. In order to insure the lower edge portion of the shoe members C remaining in snug engagement with the side wall of the tank, 5 the rim E on the central body portion of the deck is provided with spring-pressed plungers G that bear against the inner side of the shoe members C, as shown in Figure 4. It is essential that gas-tight joints be formed 10 between the various sections of the peripheral portion of the deck and also between said variable peripheral portion and the rim E on the central body portion of the deck so as to prevent the escape of gases 15 or vapors that collect in the annular space between said rim and the side wall of the tank, and in the form of my invention herein illustrated this is effected by arranging flexible sealing devices x between the various 20 sections of the variable peripheral portion of the deck and arranging a flexible sealing device y between the rim E on the central body portion of the deck and the horizontally-disposed plates D on the shoe members 25 C that lap over said rim, as described in my pending application for patent Serial No. 627,835, filed March 26, 1923 and herein shown diagrammatically. It will, of course, 30 be obvious that any other suitable means can be employed to produce gas-tight joints between the variable peripheral portion of the deck and the central body portion without departing from the spirit of my invention, and while I have herein illustrated my 35 invention embodied in a deck having a variable peripheral portion that is sustained by swinging hangers on the central body portion of the deck, I wish it to be understood that the particular design and construction of the peripheral portion of the deck and the means used to mount same on the central body portion of the deck is immaterial, so far as my invention is concerned.

40 45 The novel feature of my present invention consists in providing means for increasing the buoyancy of the outer edge of the portion of a floating deck or roof for liquid storage tanks that floats upon or is supported by the liquid in the tank. In the form of my invention herein illustrated said means consists of a plurality of pontoons or buoyant devices H connected to the central body portion of the deck adjacent the outer edge of same and projecting downwardly below the same so as to counteract the tendency of the outer edge of the central body portion of the deck to sag or deflect downwardly, due to the relatively 50 great load imposed on same by the shoe members C, horizontally-disposed plates D and hangers F that carry said parts. The pontoons H can be formed conveniently by cylindrical members arranged vertically in 55 sleeves I that project upwardly from the

central body portion B of the deck and provided with closed ends that are submerged in the liquid in the tank. Said pontoons are preferably detachably connected to the sleeves I by fastening devices 3 that pass 70 through laterally-projecting overlapping flanges on the sleeves I and pontoons H, and each pontoon is preferably provided with a removable cover J formed by a flanged cap that extends over the upper end of 75 same. By connecting the pontoons to the central body portion of the deck in this manner it is a simple matter to remove a pontoon and repair or replace it by a perfect pontoon, and in order that one or more of the pontoons may be removed without draining the tank, I make the sleeves I of such height that when a pontoon is removed the upper end portion of the sleeve from which the pontoon was withdrawn will project 80 high enough above the surface of the liquid in the tank to prevent the liquid from escaping upwardly through said sleeve and overflowing onto the central body portion 85 B of the deck.

In a floating deck of the construction above described the portion B of the deck that is supported by and floats upon the liquid in the tank will be maintained in a substantially horizontal position, even 90 though the peripheral edge of said portion is subjected to a load of relatively great weight, due, of course, to the fact that said portion is provided adjacent its outer edge with pontoons or other suitable devices that project downwardly below the underside of said portion which rests upon the liquid. The pontoons herein illustrated are only one of many forms of pontoons or buoyant devices that may be used, and while I prefer 95 to detachably connect said pontoons to the central body portion of the deck to facilitate renewal and repair of said pontoons, this is not necessary.

Having thus described my invention, what 100 I claim as new and desire to secure by Letters Patent is:

1. A floating deck for liquid storage tanks, comprising a portion that floats upon the liquid in the tank and covers the major part 115 of the surface of the liquid, pontoons or buoyant devices removably mounted in openings in said portion arranged adjacent the outer edge of same, and means for preventing the liquid in the tank from escaping 120 upwardly through one of said openings when the pontoon that co-operates with said opening is removed.

2. A floating deck for liquid storage tanks, comprising a central body portion adapted 125 to float upon the liquid in the tank, sleeves projecting upwardly from said body portion and arranged adjacent the outer edge of same, and pontoons or buoyant devices removably mounted in said sleeves.

3. A floating deck for liquid storage tanks, comprising a central body portion adapted to float upon the liquid in the tank, sleeves projecting upwardly from said body portion and arranged adjacent the outer edge of same, and pontoons or buoyant devices removably mounted in said sleeves, said sleeves being of sufficient height or depth to prevent the liquid in the tank from escaping upwardly through same and overflowing onto the body portion of the deck during the operation of removing or replacing a pontoon. ¹⁰

JOHN H. WIGGINS.
